UNITED STATES PATENT OFFICE.

IRA R. KRUG, OF PHILADELPHIA, PENNSYLVANIA.

INTERNAL-COMBUSTION-ENGINE CONTROL.

1,093,586.

Specification of Letters Patent. Patented Apr. 14, 1914.

Application filed May 8, 1913. Serial No. 765,892.

To all whom it may concern:

Be it known that I, IRA R. KRUG, a citizen of the United States, residing at Philadelphia, in the county of Philadelphia and 5 State of Pennsylvania, have invented new and useful Improvements in Internal-Combustion-Engine Controls, of which the following is a specification.

This invention relates to internal combustion engine controls, the broad object of the invention being to provide means for automatically controlling the supply of mixture to the motor in accordance with the demands of the motor under varying loads, the 15 amount of mixture passing to the engine being influenced by the velocity of the engine cooling medium during the circulation of said medium.

A further object of the invention is to 20 provide means for limiting the amplitude of movement of the throttle valve located between the source of supply of the mixture and the intake ports of the engine, in accordance with the demands of the engine 25 under variations in the load imposed thereon.

A further object of the invention is to provide, in connection with a throttle valve, and means influenced by the circulation of the cooling medium for shifting said valve 30 toward its closed position, a device for limiting the closing movement of said valve, said device embodying a plurality of stop faces, each of which is adjustable independently of the other, so as to set the throttle 35 valve in accordance with the position of the manually operated controls.

With the above and other objects in view, the invention consists in the construction, combination and arrangement of parts, as 40 will be hereinafter more fully described, illustrated in the accompanying drawings, and pointed out in the claims hereunto appended.

In the drawings: Figure 1 is a side elevation, showing the mechanism of this invention applied to the intake pipe of an internal combustion motor, said view being partly in section. Fig. 2 is a section through the same on the line 2—2 of Fig. 1, looking upward. Fig. 3 is a view similar to Fig. 1, 50 showing a part of the circulating system in section. Fig. 4 is a detail section showing the cylinder and piston construction taken at right angles to Fig. 3. Fig. 5 is a vertical section on the line 5—5 of Fig. 3. Fig. 6 is 55 a detail fragmentary perspective view of the

manually operated slide showing one of the stops and the adjusting means therefor.

In the drawings, 1 designates a carburetor forming the source of supply of the explosive mixture, and 2 the intake pipe which leads 60 from the carburetor or source of supply to the intake manifold of a multiple cylinder engine, such as is ordinarily used in automobiles, motor trucks, and the like.

In carrying out the present invention, a 65 throttle valve casing 3 is interposed between the attaching flange 4 of the carburetor and the corresponding flange 5 of the intake pipe 2, and within the central opening 6 of said casing is arranged what is known as a butterfly valve 7 in the form of a disk, the stem 8 of which extends diametrically across the opening 6 enabling said butterfly valve, which in fact constitutes the throttle valve of the engine, to entirely close or practically 75 entirely open the intake pipe 2. Mounted fast on one end of the stem 8 of said throttle valve is an elbow lever 9, to which is pivotally connected, at 10, a piston rod 11 having a joint 12 to avoid cramping. The rod 80 11 passes through a stuffing box 13 at one end of a cylinder 14 which is located in the circulating pipe 15, through which the cooling agent circulates in a manner similar to the construction now in common use in 85 internal combustion motors.

In carrying out the present invention, a branch pipe 16 leads off from the cylinder 14, which in reality forms an extension of the pipe 15, said branch pipe extending at 90 an angle from the cylinder 14 so as to provide an elongated or substantially elliptical outlet 17 for said cylinder. On the inner end of the rod 11 is a piston 18 movable back and forth in the cylinder 14, said piston being, therefore, located in the path of movement of the circulating cooling agent which is ordinarily forced through the circulating system by a pump driven by the 95 motor.

19 designates a screen arranged in the receiving end of the cylinder 14 to prevent foreign matter from entering the cylinder and interfering with the movement of the piston 18.

It will now be observed that as the cooling agent passes through the pipe 15 and through the branch pipe 16 back to the main circulating system, the pressure of the cooling agent acts against the piston 18 and 110

causes a longitudinal movement of the rod 11 which acts on the elbow lever 9 and turns the stem 8 of the throttle valve 7 toward a closed position, the movement of the valve 7 toward its closed position being in accordance with the amount of pressure of the cooling agent against the piston 18, and the amount of pressure being governed by the speed of the engine and the pump which 5 causes the circulation through the system. Therefore, should the engine start to race, the cooling agent will be forced with a greater velocity through the system acting with greater pressure on the piston 18 and 10 moving the throttle valve 7 toward its closed position, thereby immediately throttling down the engine exactly in proportion to the speed of the engine.

In order to limit the amplitude of movement of the throttle valve in the closing action thereof, the elbow lever 9 is provided with a roller 20 which is adapted to come into contact with a series of stops on a manually controlled element 21, shown in the 20 form of a slide movable perpendicularly across the intake pipe 2, to which it is attached by means of a stud or screw which passes through a guide slot 23 extending lengthwise of the slide 21.

30 Extending outwardly from the slide 21 is a series of supporting screws 24, connected to which is a corresponding series of stops 25, each of which, as shown in Fig. 6, is in the form of a spring bow provided at one 35 end with an eye 26, through which one of the screws 24 passes, the opposite or free end of said bow resting against the adjacent screw 24. The extent of projection of the stop 25 is adjusted by means of a screw 27 40 which is threaded through a flange 28 extending along the upper edge of the slide 21, the position of the screw 27 being fixed by a lock nut 29. By turning the screw 27, the radius of the arc or bow of the stop 25 45 may be increased or diminished to give the desired projection thereto, adapting the stop to act sooner or later on the roller 20 for the purpose of restricting, more or less, the closing movement of the throttle valve 7. 50 Each of the bowed stops is adjustable in the manner described and by the means referred to independently of the other stops.

The sliding element 21 is shifted back and forth by means of a connecting rod 30 which 55 has a jointed connection with an operating arm 31 fast on an operating shaft 32, so that by swinging the arm 31, the necessary movement is imparted to the slide 21 to bring the appropriate stop 25 into the path 60 of movement of the roller 20 of a throttle lever.

The arm 31 is attached to and operated by the ordinary gear shift lever (not shown) so that said arm 31 is moved backwardly 65 and forwardly in accordance with the move-

ment of the gear shift lever. It is desirable and necessary, to secure the best results, to limit the amount of gas passing to the cylinders in accordance with the increase or decrease of the speed of the engine and this is 70 accomplished by adjusting the set screws above referred to and giving more or less curvature to the members 25 thereby correspondingly varying the extent to which the butterfly or throttle valve may be opened. Thus if less gas is desired on the highest 75 speed, the corresponding screw may be turned until the butterfly valve will nearly close the passage under the influence of the pressure exerted by the circulating water on 80 the piston 18.

From the foregoing description, it will now be understood that the position of the throttle valve is regulated by the velocity of the engine cooling agent passing through the circulatory system. Therefore, when the engine has a tendency to race, it is immediately throttled by the movement of the throttle valve, the arrangement referred to being particularly valuable in case the 90 clutch is thrown out and the engine relieved of its load, the mechanism serving to immediately throttle the engine and correct the tendency of the same to race.

What is claimed is:

1. The combination with the intake pipe 95 of an internal combustion engine, of a throttle valve controlling said pipe and actuated by the current of the engine cooling medium in accordance with the velocity of said medium, and an adjustable stop for limiting positively the amplitude of movement of said valve in accordance with the requirements of the engine under varying loads.

2. The combination with the intake pipe 100 of an internal combustion engine, of a throttle valve controlling said pipe and actuated by the current of the engine cooling medium in accordance with the velocity of said medium, and an element connected with the 105 gear shift lever for limiting the amplitude of movement of said valve in accordance with the requirements of the engine under varying loads.

3. The combination with the intake pipe 115 of an internal combustion engine, of a throttle valve controlling said pipe and actuated by the current of the engine cooling medium in accordance with the velocity of said medium, an element connected with the gear 120 shift lever, and a series of stops carried by said element and acting to limit the amplitude of movement of said valve in accordance with the requirements of the engine under varying loads.

4. The combination with the intake pipe 125 of an internal combustion engine, of a throttle valve controlling said pipe and actuated by the current of the engine cooling medium in accordance with the velocity of said me-

dium, an element connected with the gear shift lever, and a series of stops carried by said element and acting to limit the amplitude of movement of said valve in accordance with the requirements of the engine under varying loads, each of said stops being adjustable independently of the others for the purpose specified.

5. The combination with the intake pipe of an internal combustion engine, of a throttle valve controlling said pipe and actuated by the current of the engine cooling medium in accordance with the velocity of said medium, an element connected with the gear

shift lever, and a series of stops carried by 15 said element and acting to limit the amplitude of movement of said valve in accordance with the requirements of the engine under varying loads, each of said stops embodying a spring bow, and means for varying the radius of the arc of said bow.

In testimony whereof I affix my signature in presence of two witnesses.

IRA R. KRUG.
